FINGER RING GUARD

Application filed August 14, 1931. Serial No. 556,952.

The present invention relates to that type of finger ring guards having outward jaws which engage and embrace the shank of the ring, the jaws being of soft bendable metal, while the elongated main member of the guard is preferably hardened to render it more or less springy.

One of the objects of the present invention is to provide a finger ring guard having 10 clasping means for securing the guard to the shank of the ring and which fully encompass the shank, in such way that the clasping means are adapted to slide more or less upon the shank. In carrying out this 15 object of the invention it is preferred that the connecting elements of the clasping means be joined together at a point which is clear of the finger bearing surface of the main member of the guard, so that the guard is kept smooth at the inner surface so as to be unobjectionable to the wearer of a ring provided with the improved guard.

Another object of the present invention is to provide the clasping means of the guard 20 with interlocking elements clear of the finger bearing surface of the main member of the guard.

A further object of the invention is to provide a finger ring guard with a pair of bendable jaws at each end which are provided with interlocking elements.

Other objects of the invention are to provide finger ring guards which are more efficient than those now on the market, in so far 35 as the guard is more positively held upon the shank of the ring, and to provide a finger ring guard of that kind, which is comparatively simple and economical of manufacture considering the functions and advantages thereof.

These being among the objects of the present invention, the same consists of certain features of construction and combinations of parts to be hereinafter described and then 45 claimed with reference to the accompanying drawings illustrating preferred forms of the invention, and wherein

Figure 1 is an enlarged elevation of a finger ring showing one form of the finger ring guard applied thereto;

Fig. 2 is a cross section of the ring on line 2—2, Fig. 1, as viewed in the direction of the arrows;

Fig. 3 is an edge elevation as viewed towards the lower part of Fig. 1;

Fig. 4 is an enlarged cross section on line 4—4, Fig. 5, showing one jaw end of the guard before the same is fastened to the ring;

Fig. 5 is a detail side elevation looking towards the right of Fig. 4;

Fig. 6 is a sectional view similar to Fig. 4 except that the jaws have been shown as partially applied to the shank of the ring;

Fig. 7 is an enlarged section of Fig. 6 on line 7—7;

Fig. 8 is a transverse section similar to Fig. 6, but showing the jaws at one end of the guard as fully applied to the ring;

Fig. 9 is an enlarged section of Fig. 8 on line 9—9, showing how the jaws interlock;

Fig. 10 is a detail side elevation of a portion of a ring and improved guard of modified construction, before the guard is fastened to the ring;

Fig. 11 is a section of Fig. 10, mostly an elevation, as viewed from the left of said figure;

Fig. 12 is a plan of one end of the guard and a portion of a ring, showing the jaws as partially applied to the ring;

Fig. 13 is a view similar to Fig. 12, except that the jaws are shown as fully applied to the ring;

Fig. 14 is a section on line 14—14 of Fig. 12;

Fig. 15 is a section of a ring showing one end of another modified form of the guard before it is fastened to the ring;

Fig. 16 is an outer elevation of this form of the guard, as partially applied to the ring;

Fig. 17 is a view similar to Fig. 16 showing one end of the guard fully applied to the ring;

Fig. 18 is a transverse section on line 18—18 of Fig. 17;

Fig. 19 is a section of a ring showing a further form of the invention before the jaws are fastened to the ring;

Fig. 20 is a side elevation of Fig. 19;

Fig. 21 is an outside elevation to show the jaws of Fig. 19 as completely fastened to the ring; and

Fig. 22 is a broken inner elevation of the 5 locked jaws.

The preferred form of the invention is disclosed in Figs. 1 to 9 inclusive. In Fig. 1 a ring 10 with a setting 11 is shown, which ring and setting may be of any desired arrangement and construction, the setting being illustrated only conventionally:

In said figures there is disclosed an elongated member 12 which is the main member of the guard, the latter being preferably 15 composed entirely of metal, say 14 carat gold. The elongated member 12 is thin and flexible and is preferably hardened relatively to the two pair 13, 14 of jaws, one pair at each end of and preferably formed integral- 20 ly with the flexible member 12. When the jaws are integral with the flexible member 12, they are preferably softened relatively thereto so as to be bendable or more or less deformable. As shown in Figs. 4 and 5 each 25 pair of jaws includes jaws 15, 16 which are bendable one towards the other. It is preferred that when a guard of such construction, that is with a pair of jaws at each end, is provided, that the jaws extend outwardly 30 in substantially parallelism, so as to facilitate the application of the guard to the shank of a ring and the final fastening of the guard thereto.

In Figs. 4 and 5 the jaw 15 is shown as 35 provided with a pair of bendable prongs or interlocking elements 17, which may be bent inwardly away from the body of the jaw 15 so as to extend towards the other jaw 16. Preferably these prongs 17 are bent so as to 40 diverge slightly outwardly from the body of the jaw 15, as shown in Fig. 7.

Jaw 16 is provided with an end portion 18 which is relatively wide as compared with the inner portion of the jaw, as shown 45 in Fig. 5. A longitudinal slot or opening 19 is formed in the relatively wide portion 18, so as to provide longitudinal and substantially parallel side bars 20, 20, one at each side of such opening.

50 The outer extremities of the side bars 20, 20 are connected by an end bar 21 which closes that end of the opening 19. As shown in Figs. 4 and 6, the end bar 21 is thinner than the thickness of the jaw 16, so as to 55 provide a shallow recess 22 extending across the outer extremity of the jaw and at the outer surface thereof, as shown in Fig. 5.

Figs. 5, 7 and 9 disclose that the side bars 60 20 are provided at their adjacent edges with inner, beveled, surfaces 23, which surfaces flare outwardly away from the inner edges of the side bars 20, 20.

The preferred manner of applying a guard 65 provided at each end with a pair of jaws simi-

lar to those illustrated in Figs. 4 and 5 will now be described.

The elongated flexible member 12 is applied to the inside of the shank of the ring so that the pair of jaws at each end of the guard extend outwardly at each side of the shank 10. The jaws being composed of bendable metal, the jaw 16 is bent inwardly in a curve so as to extend transversely over the outer surface of the shank 10, as shown in Fig. 6. Then the jaw 15 is bent over far enough as shown in broken lines, so as to register the prongs or interlocking elements 17 with the opening 19 in the jaw 16, shown also in Fig. 7. The end of the jaw 15 is now pressed down far enough so as to enter the prongs 17 through the opening or slot 19 in the jaw 16, and firmly enough so that by the engagement of the prongs with the outer surface of the ring shank, said prongs will be spread apart as shown in Fig. 9, and to be bent outwardly thereby so as to come in contact with the beveled surfaces 23, at opposite sides of the opening 19. When each pair of jaws of this form of the invention is properly secured over the shank of the ring so as to encompass the same, the jaws are interlocked together and suitably connected for reliably holding the guard on the ring. When the body of the jaw 15 has been bent fully down as shown in Fig. 8, the same will engage in the shallow recess 22 at the extremity of jaw 16.

No tools other than the human fingers are necessary in applying the improved guard to a finger ring, so that it is not necessary 100 to mar the ring or the guard at all, and when the guard, as shown in Figs. 1, 2 and 3, is fully fastened to the ring, the clasping means at each end thereof will allow the elongated flexible member to be flexed more or less as required by the particular finger on which the ring is worn, because the clasping means at each end when properly encircling the shank of the ring will have a slide fit thereon, that is the interlocked jaws may be moved in one 105 or the other direction. It will be seen that when firmly pressing down the prongs 17 of jaw 15 from the position shown in Fig. 7 to that shown in Fig. 9, the outer surface of the ring shank constitutes an anvil which acts to 110 deform and spread the prongs relatively to the jaw 15. Thereby a positive and secure interlocking connection is provided for the ring encompassing jaws.

In Figs. 10 to 14 inclusive there is illustrated a modified construction of the improved finger ring guard, according to the present invention. In these figures the elongated flexible member 24 of the guard is provided at each end with a pair of bendable 120 jaws 25, 26. One pair only is shown, as the other pair is preferably constructed in the same manner. These jaws 25, 26, extend outwardly in substantial parallelism, in the form in which the guard is preferably deliv- 125

ered to the customer, so as to facilitate application to the finger ring 10. Jaw 25 is provided at its extremity with a relatively wide transverse portion 27, so that the said jaw is substantially T-shaped, or otherwise, providing that a relatively wider transverse portion is furnished. The transverse portion 27 is shown in Fig. 11 as thinner than the body of the jaw 25, so as to provide outer depressions 28, one at each side of the body of the jaw.

Referring more particularly to Figs. 10 and 12, it will be seen that the other jaw 26 is provided with bifurcations 29, so as to constitute a sort of fork. These bifurcations diverge preferably outwardly from the body of jaw 26, that is to say, the bifurcations 29 converge at their inner ends. The bifurcations 29 are separated so as to provide a space 30, while the outer extremities of the bifurcations are provided with inwardly directed prongs or interlocking elements 31, 32, the extremities of these prongs being preferably spaced apart a distance approximately that of the width 25 of the narrowest portion of the jaw 25, so that they may pass such portion. The laterally directed prongs 31, 32 are preferably thinner than the adjacent portions of the bifurcations 29 so as to provide depressions 33 at the outer surface of the jaw 26. There is also a shallow recess 34 at the inner side of the jaw 25 and a similar shallow recess 35 in each bifurcation element 29.

Referring to Fig. 12 it will be seen that in order to apply this modified construction of finger ring guard to a ring, the bendable jaw 25 is first folded down and upon the outer surface of the ring, and then the jaw 26 is folded down, when the bifurcations 29 will be disposed over the widened portion 27, with the mutually presented prongs 31, 32 disposed at opposite side edges of the body or stem of the jaw 25. The position of the inwardly directed prongs 31, 32 will then be such that by deflecting or pressing the bifurcations 29 together, the bifurcations will be brought into substantial parallelism and the prongs 31, 32 caused to engage under the jaw 25 at points between the widened portion 27 and one edge of the shank of the ring, as shown in Fig. 13. The under recess 34 in jaw 25 will permit the prongs to enter, and when the jaws are thus interlocked, the clasping means formed thereby will fully encompass the outer surface of the shank of the ring and a neat and reliable connection be formed thereby. Fig. 14 illustrates how the clasping means appear in side elevation when applied to the ring, as shown in Fig. 13.

In Figs. 15 to 18 inclusive there is disclosed a further modification of the invention. In this modification the elongated flexible member 36 is provided at one end with a pair of bendable jaws 37, 38, it being understood that the other end of the said

member may be provided with a similar pair of bendable jaws. The jaw 37 is provided near its terminal with a pair of lateral recesses 39, one in each edge of the jaw, whereby a head or widened portion 39a is provided at the terminal of said jaw. The opposite jaw 38 is provided at its terminal with a pair of prongs or lips 40 which become thinner toward their free edges. These prongs or lips 40 are preferably bent in the course of manufacture so that they will extend inwardly from the jaw 38, and the two jaws are formed so as to extend in substantial parallelism, as shown in Fig. 15, whereby to facilitate the application of the pair of jaws and member 36 to the shank or ring 10.

In applying this form of the invention to the shank of the ring, the jaws 37, 38 are passed thereover so as to extend outwardly from the ring, and then jaw 39 is bent downwardly and inwardly over the outer surface of the shank, as shown in Fig. 16. Thereafter the jaw 38 is bent downwardly and inwardly over the shank so as to cause the thinner edges of the prongs or lips 40 to register with the recesses or notches 39 in jaw 37, and inasmuch as the thinner free edges of the prongs are directed slightly one towards the other, a further pressure upon the terminal of jaw 38 will force the prongs or lips 40 underneath the notched portion of jaw 37, the outer surface of the shank of the ring serving as an anvil surface to bend the prongs or lips inwardly under the jaw 37, as shown in Figs. 17 and 18. The parts are so proportioned that when they are properly interlocked together, the clasping means will have a slide fit upon the shank of the ring, permitting the flexibly elongated member 36 to flex and accommodate itself to the finger wearing the ring.

Figures 19, 20, 21 and 22 illustrate another modification wherein the jaws are hooked together and interlocked by deflecting them laterally or edgewise. In these views the elongated flexible member 41 is provided at each end (one end only being shown) with a pair of bendable jaws 42, 43. These are arranged so as to extend in substantial parallelism, when delivered to the customer, so as to facilitate application of the guard to the finger ring. Each of the jaws is provided with a lateral notch 44 in one edge, the two notches extending in opposite direction from the jaws, so that when the jaws are slightly deflected from each other edgewise and bent down and over the ring shank, the hooks 45 and the jaws may be pressed together in a lateral direction, thereby bringing the respective hooks underneath the respective jaws and into under shallow recesses 46 formed therein, thereby causing the clasping means to encompass the outer surface of the ring shank and to interlock the jaws together. Each of the hooks or prongs

45 is thinner than its jaw and each of the notches 44 is cut at one side at an inclination transversely of the jaw, and when the jaws are brought together as in Fig. 21, the thick 5 inclined edge terminals of the jaws will be brought together in abutment, along a line 47 which is on the bias with respect to the connected and interlocked jaws, the inner edges of the jaws holding them from separation, 19 (Fig. 22).

It will thus be seen that the present invention is susceptible to various modifications of the clasping means, and, when the guard is applied to a finger ring, such means and the 15 adjacent portion of the elongated flexible member will entirely encompass the shank of the ring, and as the members of the clasping means are interlocked, a reliable, convenient and desirable ring guard is provided, having 20 clasping means allowing more or less flexing of the elongated guard member, which accommodates itself to the size of the finger wearing the ring.

Still other modifications may be resorted 25 to, as will be obvious to those skilled in the art, without departing from the spirit of the invention as defined in the appended claims.

What I claim as new is,—

1. A finger-ring guard, comprising an elongated member and clasping means carried thereby and adapted in conjunction with such member to fully encompass the shank of a ring, such means including interlocking elements engageable at a point clear of the finger bearing surface of the elongated member.

2. A finger-ring guard, comprising a flexible elongated member and clasping means carried thereby and adapted in conjunction with such member to fully encompass the shank of a ring, such means including interlocking elements engageable at a point clear of the finger bearing surface of the elongated member, some of the elements being bendable in a direction laterally of the clasping means.

3. A finger-ring guard, comprising an elongated member and clasping means carried thereby and adapted in conjunction with such member to fully encompass the shank of a ring, such means including a pair of bendable jaws having interlocking elements engageable at a point clear of the finger bearing surface of the elongated member.

4. A finger-ring guard, comprising a flexible elongated member and a pair of bendable jaws extending outwardly from each end of the member, and the free ends of the jaws adapted to meet, the member and jaws being composed of metal, and interlocking elements at the free ends of the jaws whereby to hold the jaws around the shank of a ring and the member inside of the ring.

5. A finger-ring guard, comprising a flexible elongated member and a pair of bendable jaws extending outwardly from each end of the member, and the free ends of the jaws

adapted to meet, the member and jaws being composed of metal, and interlocking elements at the free ends of the jaws and extending laterally thereof whereby to hold the jaws around the shank of a ring and the member 70 inside of the ring.

6. A finger-ring guard, comprising a flexible elongated member and a pair of bendable jaws extending outwardly from each end of the member, and the free ends of the jaws 75 adapted to meet, the member and jaws being composed of metal, and laterally extending hook elements at the free ends of the jaws whereby to hold the jaws around the shank of a ring and the member inside of the ring. 80

7. A finger-ring guard, comprising a flexible elongated member and a pair of bendable jaws extending outwardly from each end of the member, and the free ends of the jaws adapted to meet, the member and jaws being composed of metal, the free end of one jaw having an opening and the free end of the other jaw a deformable projection to engage in the opening. 85

8. A finger-ring guard, comprising a flexible elongated member and a pair of bendable jaws extending outwardly from each end of the member, and the free ends of the jaws adapted to meet, the member and jaws being composed of metal, the free end of one 90 jaw having an opening and the free end of the other jaw a pair of lateral deformable projections to engage in the opening. 95

9. A finger-ring guard, comprising a flexible elongated member and a pair of bendable jaws extending outwardly from each end of the member, and the free ends of the jaws adapted to meet, the member and jaws being composed of metal, the free end of one 100 jaw having an enlargement provided with a slot extending longitudinally of such jaw and the free end of the other jaw having a pair of deformable prongs adapted to enter the slot and to be spread apart to mechanically connect the jaws together. 105

10. A finger-ring guard, comprising an elongated member and a pair of bendable jaws extending outwardly from each end of the member, and the free ends of the jaws being adapted to meet, the member and jaws being composed of metal, and the free end of one jaw being wider than its body and the free end of the outer jaw being bifurcated, the bifurcations being deformable to engage under the body of the opposite jaw and the wider end adapted to engage under the bifurcations. 110

11. A finger-ring guard, comprising an elongated member and a pair of bendable jaws extending outwardly from each end of the member, and the free ends of the jaws being adapted to meet, the member and jaws being composed of metal, and the free end of one jaw being wider than its body and the free end of the other jaw being bifurcated, 115 120 125 130

the bifurcations converging and being deformable to engage under the body of the opposite jaw and the wider end adapted to engage under the bifurcations.

5 12. A finger-ring guard, comprising a flexible elongated member and a pair of bendable jaws extending outwardly from each end of the member, and the free ends of the jaws adapted to meet, the member and jaws being composed of metal, the free end of one jaw having a T-head and the free end of the other jaw being bifurcated and the bifurcations forming mutually presented prongs, the bifurcations being deformable to engage the prongs under the opposite jaw and the T-head adapted to engage under the bifurcations.

10 13. A finger-ring guard, comprising a flexible elongated member and a pair of bendable jaws extending outwardly from each end of the member, and the free ends of the jaws adapted to meet, the member and jaws being composed of metal, the free end of one jaw having a T-head and the free end of the other jaw being bifurcated and the bifurcations diverging from their jaws and having mutually presented prongs, the bifurcations being deformable to engage the prongs under the opposite jaw and the T-head adapted to engage under the bifurcations.

15 14. A finger-ring guard, comprising a flexible elongated member and a pair of bendable jaws extending outwardly from each end of the member, and the free ends of the jaws adapted to meet, the member and jaws being composed of metal, the free end of one jaw having lateral recesses and the free end of the other jaw having a pair of inwardly bendable prongs adapted to enter the recesses and be bent under the recessed jaw.

20 15. The combination with a finger ring, of a guard comprising an elongated member and clasping means extending outwardly from each end of the member and fitting on and completely surrounding the shank for fixing the elongated member along the inner surface of the ring, each such means including interlocked elements which are engaged at a point between the planes of the side edges of the elongated member.

25 16. The combination with a finger ring, of a guard comprising a flexible elongated member and clasping means extending outwardly from each end of the member and fitting on and completely surrounding the shank for fixing the elongated member along the inner surface of the ring, each such means including interlocked elements which are engaged at a point between the planes of the side edges of the elongated member, some of the elements extending transversely of the clasping means.

30 17. The combination with a finger ring, of a guard comprising an elongated member and clasping means extending outwardly from

each end of the member and fitting on and completely surrounding the shank for fixing the elongated member along the inner surface of the ring, each such means including a pair of meeting jaws having interlocked elements which are engaged at a point between the planes of the side edges of the elongated member.

35 18. A finger-ring guard, comprising an elongated member and clasping means carried thereby and adapted in conjunction with such member to fully encompass the shank of a ring, such means including connecting elements joined together at a point clear of the finger bearing surface of the elongated member.
